US0D1013293S

(12) **United States Design Patent** (10) **Patent No.:** **US D1,013,293 S**
(45) **Date of Patent:** **** Jan. 30, 2024**

(54) **GRINDING HEAD FOR NAILS**

(71) Applicants: **Longhui Wan**, Guangdong (CN);
Huang Lei, Huaihua (CN)

(72) Inventors: **Longhui Wan**, Guangdong (CN);
Huang Lei, Huaihua (CN)

(**) Term: **15 Years**

(21) Appl. No.: **29/885,325**

(22) Filed: **Feb. 23, 2023**

(51) LOC (14) Cl. **30-99**

(57) **CLAIM**

The ornamental design for a grinding head for nails, as shown and described.

DESCRIPTION

FIG. 1 is a front, left and top perspective view of a grinding head for nails, showing our design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

1 Claim, 8 Drawing Sheets
